UNITED STATES PATENT OFFICE.

WILLIAM W. MCCHESNEY, OF NEW YORK, N. Y., ASSIGNOR TO WILLIAM H. RANDALL,
OF HUNTINGTON, NEW YORK.

DESIGN FOR A CROCHET-COTTON HOLDER.

45,914.

Specification for Design.

Patented June 9, 1914.

Application filed March 31, 1914. Serial No. 828,630. Term of patent 7 years.

To all whom it may concern:

Be it known that I, WILLIAM W. MCCHESNEY, a citizen of the United States, residing at New York, borough of Brooklyn, in the county of Kings and State of New York, have invented a new, original, and ornamental Design for a Crochet-Cotton Holder, of which the following is a specification, reference being had to the accompanying drawing, forming part thereof.

The figure is a perspective of a crochet-cotton holder showing my new design.

I claim:

The ornamental design for a crochet-cotton holder, as shown.

WILLIAM W. MCCHESNEY.
